COMBINED AUTOMOBILE WATCH AND BRACKET

Albert Hajjar, Brooklyn, N. Y.

Application December 8, 1954, Serial No. 33,452

Term of patent 7 years

(Cl. D42—7)

FIG. 3

FIG. 4

To all whom it may concern:

Be it known that I, Albert Hajjar, a citizen of the United States, residing at Brooklyn, in the county of Kings and State of New York, have invented a new, original and ornamental Design for a Combined Automobile Watch and Bracket, of which the following is a specification, reference being had to the accompanying drawing, forming part thereof.

In the drawing:

Fig. 1 is a side elevational view of a combined automobile watch and bracket, showing my new design;

Fig. 2 is a top plan view thereof;

Fig. 3 is an end elevational view thereof, looking from the right of Fig. 1; and

Fig. 4 is an end elevational view thereof, looking from the left of Fig. 1.

I claim:

The ornamental design for a combined automobile watch and bracket, as shown.
